UNITED STATES PATENT OFFICE

144,710

DESIGN FOR A SODA STRAW DISPENSER

Henry A. Gosling, Chicago, Ill., assignor of one-half to Frank P. Case, Chicago, Ill.

Application August 6, 1945, Serial No. 121,250

Term of patent 7 years

(Cl. D1—12)

To all whom it may concern:

Be it known that I, Henry A. Gosling, a citizen of the United States, residing at Chicago, in the county of Cook and State of Illinois, have invented a new, original, and ornamental Design for a Soda Straw Dispenser, of which the following is a specification, reference being had to the accompanying drawing, forming a part thereof.

In the drawing:

Fig. 1 is a front perspective view of a soda straw dispenser showing my new design; and

Fig. 2 is a rear perspective view of the soda straw dispenser showing my new design.

I claim:

The ornamental design for a soda straw dispenser, as shown.

HENRY A. GOSLING.
